UNITED STATES PATENT OFFICE.

RICHARD MONTGOMERY RODDEN, OF MONTREAL, QUEBEC, CANADA.

COLLAR.

1,102,440.

Specification of Letters Patent.

Patented July 7, 1914.

Application filed December 22, 1911. Serial No. 667,284.

To all whom it may concern:

Be it known that I, RICHARD MONTGOMERY RODDEN, of the city of Montreal, in the Province of Quebec and Dominion of Canada, have invented certain new and useful Improvements in Collars, of which the following is a full, clear, and exact description.

This invention relates to improvements in 10 collars, and the object is to provide a collar of a double or folded variety which will have all the pliability and freedom of movement at the front which a single collar has.

A further object is to provide a fold collar 15 having the upper corners thereof free to move independently, said collar being so constructed that these corners will normally remain in engagement so that the wearer's neck will not be visible therebetween.

Still another object is to provide a collar 20 so constructed that the tie will be held at the lower portion thereof.

In the present form of fold collars, the 25 attaching tongues are made the full depth of the inner flap or neck band of the collar, one of these tongues being given an upward turn so as to closely engage the fold between the inner and outer flaps of the collar and hold the ends of the collar together. The 30 disadvantage of this form is that there is no flexibility at the front of the collar with the result that a person with a large larynx who desires to wear this form of collar is compelled to either wear a very low collar or 35 else endure the irritation of the unyielding collar pressing against his larynx.

To accomplish these objects I provide a collar of substantially the usual fold type having an inner flap or neck band which 40 may be connected either to the top of the collar or to an inwardly folded extension thereof. The neck band is provided with attaching tongues projecting beyond the ends of the outer flap so as to be overlapped and 45 hold the ends of the outer flap in abutting or approximately abutting relation. These attaching flaps are made only a part of the depth of the neck band and are located at the lower portion thereof, so that the upper 50 portion of the neck band is free to be sprung outwardly and carry with it the corners of the outer flap. Small supplementary flaps are secured to the neck band to provide a suitable hold for the attaching tongues, so 55 that the same will be enabled to normally

hold the edges of the collar together in the usual manner.

In the drawings which illustrate this invention:—Figure 1 is a perspective view of the collar as seen from the front when worn. 60 Fig. 2 is a perspective view of the collar seen from the back and showing the structure of the inner fold. Fig. 3 is a perspective view similar to Fig. 1, showing one of the corners of the outer flap raised and 65 pulled forward to illustrate the flexibility of the collar. Fig. 4 is a cross sectional view showing the attachment of one of the supplementary flaps. Fig. 5 is a plan view of a slightly alternative form of collar flat- 70 tened out.

Referring more particularly to the drawings, 11 designates the outer flap of a fold collar and 12 the inner flap or neck band of same, said flaps being preferably connected 75 at their upper edges as indicated at 13. The neck band is provided at its ends with attaching tongues 14 and 15, said tongues being located at the lower portion thereof, so that the upper part of the ends of the neck 80 band are entirely disconnected. These upper portions of the end of the neck band are preferably formed at an angle, as shown at 16, so that when the ends of the collar are brought together a triangular space is 85 formed between the ends of the neck band and the upper edges of the tongues, as clearly shown in Fig. 2. The ends of the neck band above the tongues may if desired be perpendicular instead of sloped, and in 90 any case the spring of the material forming the collar will normally hold the upper portions of the neck band in position but will allow the same to be bent outwardly without straining the collar fastening. The upper 95 edge 17 of the tongue 15 is upwardly curved in the usual manner for the purpose of holding the ends of the collar closely together. Since this tongue cannot rest in the fold between the inner and outer flaps of the collar, 100 it is necessary to provide a supplementary flap 18 secured to the outer surface of the neck band adjacent each end thereof. The upper edge of the tongue engages under this flap 18 and operates in the well known manner to hold the ends of the collar closely together. While only one flap is required for 105 this purpose a duplicate flap is placed on the other end of the collar so that the wearer may slip the neckband of his tie under these 110

flaps to prevent the tie from riding up and restricting the flexibility of the upper portion of the collar. The flap 15 is provided with a triangular aperture 20 having an eyelet 21 of suitable size to accommodate the shank of a collar button communicating with the triangular opening at the apex thereof, said triangular opening being of a suitable size to admit the head of a collar button.

10 The modification shown in Fig. 5 consists in folding the outer flap 11 of the collar at the line 22 which corresponds to the fold occurring at the line 13 in the other figures. The portions 23 of the flap 11 which are 15 folded inwardly are connected to the neck band 12 at a line of stitching 24, which line curves from the upper edges of the tongues 14 and 15 to the fold 22 at the back of the collar. The supplementary flaps 18 20 are secured by the line of stitching 24 which connects the outer flap to the neck band.

It will be readily seen from the drawings that since the upper portions of the neck band are not connected by the tongues that 25 they will be free to move outwardly and carry with them the upper portions of the outer flap 11. In fact in laundrying the collars, these upper portions designated 19 may be given a slight outward turn as indicated in the drawings, in order to provide 30 additional room and prevent the wearer's larynx from coming in contact with the edges or corners of the collar. With fold collars of the usual type, when the head is bent forward a certain tightness at the throat is experienced which is caused by the rigid upper edge of the collar pressing against the wearer's throat. In the collar shown in this invention, when the head is bent forward, 35 the corners 19 of the collar move outwardly and separate more or less, thus allowing the wearer's neck to move naturally without any restriction. The ends of the neck band being undercut, as shown at 16, allow the corners 40 of the collar to move outwardly without forming a V-shaped notch which would tend to close and pinch the wearer's skin when the head was raised.

In putting on the collar great ease is experienced for the reason that after the 50 tongue 14 has been secured in position, the front of the collar may be conveniently opened to allow the easy insertion and fastening of the tongue 15 by merely raising and at the same time pulling forward the 55 lower corner of the outer fold, as indicated in Fig. 3. This movement of the collar enables the tongue 15 to be fastened without bending or straining the same, so that the life of the collar is considerably prolonged. 60 In fastening the tongue 15 into place, the triangular opening 20 is placed over the collar button and the tongue drawn downwardly, so that the shank of the button slips easily into the eye 21. When the tongue is in 65 position under the flap 18, it will be prevented from rising and slipping off the collar button. When the corners 19 of the collar are bent outwardly there is no appreciable stress thrown on the tongue 15 as 70 the movement of the corners is more forwardly than laterally, and is resisted chiefly by the spring of the stiff material.

Having now fully described my invention, 75 what I claim is:—

In a collar an outer flap and an inner flap connected at their upper edges, attaching tongues on the lower portion of the inner flap at the ends thereof, and a supplementary flap secured to said inner flap in position to engage said tongues, said supplementary flap being below the upper edges of 80 said inner and outer flaps, the opposing edges of the upper portion of said outer flap being parallel, and the opposing edges 85 of the upper portion of said inner flap being separated a gradually increasing distance from the upper edge of the collar to the upper edge of said tongues.

In witness whereof I have hereunto set 90 my hand in the presence of two witnesses.

RICHARD MONTGOMERY RODDEN.
